CHAIR AND DESK COMBINATION OR THE LIKE

Alfred C. Hoven, William S. Lindberg, and Walter E. Nordmark, Grand Rapids, Mich., assignors to American Seating Company, Grand Rapids, Mich., a corporation of New Jersey

Application September 26, 1955, Serial No. 38,099

Term of patent 14 years

(Cl. D15—1)

The characteristic features of the design reside in the portions shown in full lines.

We claim:

The ornamental design for a chair and desk combination or the like, substantially as shown and described.
